UNITED STATES PATENT OFFICE.

FRANK E. KING, OF WEST LEBANON, NEW HAMPSHIRE.

PIANO-TUNING PIN.

SPECIFICATION forming part of Letters Patent No. 247,363, dated September 20, 1881.

Application filed January 3, 1881. (No model.)

To all whom it may concern:

Be it known that I, FRANK E. KING; of West Lebanon, in the county of Grafton and State of New Hampshire, have invented certain new and useful Improvements in Piano-Tuning Pins, of which the following is a specification.

The object of my invention is to provide a tuning-pin for pianos, which shall not become loose and move under the force of the tension of the string when repeatedly struck upon by the hammer when in use, but that such tension as may be required in turning the said string shall remain fixed and positive, thus avoiding the frequent necessity of retuning, as is common with those heretofore constructed and now in general use; and it consists in the construction, combination, and arrangement of the several parts of the device, as hereinafter more fully described and set forth.

Figure 1 represents a perspective view of my invention. Fig. 2 represents a vertical section of the same.

A represents the wrest plank or frame of a piano provided with a suitable series of holes to correspond with the strings B, as usual. Into these holes are securely driven the vertical studs or pins E, provided with a horizontal hole, C, arranged in the direction of the string D, one end of which is secured in the usual manner, and the opposite adjustable end passed through a hole, H, formed in the downward or upward projecting end of the adjustable string-holder F, and the slack of the said string B wound around such projecting end portion, the opposite screw-threaded portion having upon its upper surface a longitudinal groove, P, and adapted to fit loosely within the horizontal hole C of the stud or pin E when placed therein, and provided with a suitable screw-nut, N, which may be turned with a wrench or key, so as to tune the said string D, by drawing the said holder F through the

hole in the stud or pin E, against which the said screw-threaded tuning-nut has a bearing 45 at its opposite side. When the said string D is correctly tuned the set-screw L, fitted into a corresponding hole formed in the top end of the stud or pin E, and having a bearing upon the check-bolt K, the upper end of which is 50 provided with a projecting pintle or steadyng-pin, J, which fits into a corresponding hole in the lower end of the said set-screw L, being turned or screwed inward, forces the lower end of the said check-bolt K firmly against the bottom of the groove P, formed in the string-holder F, so as to prevent vibratory movement of the same through its connections with the said vibrating string D.

Having thus described my invention, what I claim is—

1. A piano-tuning pin consisting of the vertical stationary stud or pin E, having a horizontal hole, C, provided with the adjustable string-holder F, having a downward or upward projecting end adapted to hold the string, and provided with a longitudinal groove, P, to receive the end of the check-bolt K, held therein by the set-screw L, the said string-holder F being adjusted by means of the screw-threaded 65 nut N so as to tune the string D, substantially 70 as described.

2. The combination, with the wrest-plank, of the stationary vertical stud or pin E, having the horizontal hole C, and provided with the vertical check-bolt K and set-screw L, and the adjustable string-holder F, provided with the screw-threaded tuning-nut N, and having the longitudinal groove P, all being constructed and arranged to operate substantially in the 75 manner described, as and for the purposes set forth.

FRANK E. KING.
